CLAIM

The ornamental design for a handlebar for cycle or motorcycle as shown and described.

DESCRIPTION

FIG. 1 is a top-front-left side perspective view of a handlebar for cycle or motorcycle embodying our new design; FIG. 2 is a rear elevation view thereof; FIG. 3 is a front elevation view thereof; FIG. 4 is a left side elevation view thereof; FIG. 5 is a right side elevation view thereof; FIG. 6 is a top plan view thereof; FIG. 7 is a top-rear-right side perspective view thereof; and, FIG. 8 is a bottom plan view thereof. Elements drawn in broken lines illustrate portions of the handlebar which do not form part of the claimed design.

1 Claim, 8 Drawing Sheets
